LOOSE LEAF BINDER

Edward H. Zerbe, Grosse Pointe Park, Mich., assignor to The Burkhardt Company, a corporation of Michigan

Application March 31, 1938, Serial No. 199,148

1 Claim. (Cl. 129—17)

This invention relates to loose leaf binders in which a plurality of prongs are utilized for retaining filler sheets therein.

In angle back prong binders it has been customary to use at least four prongs, two on each angle of the angle back positioned in staggered relationship to the prongs on the opposite angle back. This requires the use of filler sheets having four holes therein. The general use of ring binders has brought about the use of three hole filler sheets. Obviously, if three prongs were used in prong binders, the sheets impaled in one half of the binder on one prong would be difficult to register with the sheets impaled in the other half of the binder on the other two prongs when closing the binder.

Ring binders are not desirable because of the fact that, when a ring binder is opened, sheets cannot be turned and transferred from one side thereof to the other without removing them from one half of the open rings and re-impaling them on the other half of the open rings.

A step forward in providing a hinged angle back prong binder for use with standard three hole prong sheets was disclosed in the application for patent of Stanley G. Johnson, Serial No. 62,885, filed February 8, 1936, which issued into Patent No. 2,110,366 entitled Loose leaf binder on March 8, 1938, wherein pairs of opposed half round leaf impaling prongs adapted to register with each other when the binder is partially or fully closed were used. However, when the binder disclosed in Patent No. 2,110,366 is partially opened, the half round leaf impaling prongs on one side present their flat sides and sharp lower edges as guides for the filler sheets impaled thereby with the result that the filler sheets on one side of the binder when partially open are subject to being easily torn out by accident or the apertures therethrough become so enlarged that the said filler sheets present a sloppy and disorderly appearance within the binder.

With the foregoing in view, one object of this invention is to provide a loose leaf binder having all the desirable attributes of ring binders and prong binders combined and which may be constructed at a cost below that of the usual prong binder or ring binder.

Another object of the invention is to provide a prong binder adapted to impale three hole filler sheets with four prongs and accurately hold the filler sheets with two prongs when the binder is open for engagement by the other two prongs of the binder during the closing thereof.

Another object of the invention is to provide a

novel loose leaf binder employing the combination of two round and two half round leaf impaling prongs for engaging three hole filler sheets as a three prong binder when closed and as a four prong binder when partially or fully opened.

Another object of the invention is to provide an angle back prong binder in which both split prongs and round prongs are employed to advantage with the rounded side and not the flat sides and the sharp lower edges of the half round prongs serving as guides for the filler sheets impaled thereby.

Other objects of the invention will become apparent by reference to the following detailed description taken in connection with the accompanying drawings, in which:

Fig. 1 is a view part in cross section and part in end elevation showing a loose leaf binder embodying the invention.

Fig. 2 is an inside plan view of the binder disclosed in Fig. 1 positioned on its back with the covers broken away and the loose leaf filler sheets removed, a portion of the view being shown in section to better illustrate the construction.

Fig. 3 is an inside plan view of the binder similar to Fig. 2 showing the binder with filler sheets therein.

Fig. 4 is an enlarged cross sectional view taken on the line 4—4 of Fig. 2 showing the binder locked in a closed position.

Fig. 5 is an enlarged plan view of the locking device of the binder when in a closed position.

Fig. 6 is a view in perspective showing the binder with filler sheets therein in its partly open position.

Fig. 7 is a view in perspective showing the binder with filler sheets therein in its fully open position.

Referring now to the drawings wherein like numerals refer to like and corresponding parts throughout the several views, the embodiment of the invention disclosed therein comprises a loose leaf binder in which two angles 10 and 11 are hinged together along the center of the back thereof around a hinge pin 12. The upstanding legs of the angles 10 and 11 are preferably provided with end pieces 13 and 14 on angle 10 and end pieces 15 and 16 on angle 11, the said end pieces being preferably formed integral with the angles 10 and 11. However, the said end pieces may be formed separate from the said angles of the angle back and secured thereto in any suitable manner.

The pairs of end pieces 13 and 15, and the pairs of end pieces 14 and 16, cooperate with

each other to form a closure at the ends of the U-shaped back 17 of the binder. The said pairs of end pieces cooperate with each other to serve as a stiffening and guide means for maintaining the upstanding legs of the hinged angles 10 and 11 in their normal position. A suitable locking device adapted to hold the binder in a closed or semi-open position is preferably mounted on a pair of end pieces as hereinafter described in detail.

The upstanding leg of each of the angles 10 and 11 of the angle back of the prong binder disclosed in the drawings is preferably provided with one round prong 18 projecting therefrom near one end thereof and a half round prong 19 projecting therefrom at the center thereof. The said half round prongs 19 are oppositely disposed with respect to each other and are arcuately formed in such a manner that when the binder is partially or fully closed the said prongs 19 cooperate with each other and form a ring as shown in Figs. 2, 3 and 6. Each round prong 18 is located in spaced relationship from the flat side of the half round prong 19 projecting from the same angle of the angle back of the binder from which the round prong projects a distance equal to the spacing of the center and extreme punched holes 20 in the filler sheets 21 as best shown in Figs. 2, 3, 6 and 7. The said round prongs 18 are formed to the same arc as the said half round prongs 19 whereby to permit the filler sheets 21 impaled thereby to be engaged by both round prongs 18 and both half round prongs 19 without wrinkling or bulging.

35 The upstanding legs of the angles 10 and 11 are preferably provided with a plurality of substantially frusto-conical shaped depressions 22 which have suitable other than round apertures punched in the base thereof through which the suitably 40 shouldered other than round heel of the prongs 18 and 19 are positioned and headed as best indicated in Figs. 2 and 4, the shoulder 23 and head 24 of the said prongs 18 and 19 tightly gripping the metal at the base of the said frusto-conical 45 depressions 22. Although the prongs 18 and 19 have been shown and described as riveted to the said angles 10 and 11 of the angle back of the binder, it is obvious that the said prongs may be welded or otherwise secured to the said angles 10 and 11.

The frusto-conical depressions 22 are provided in the upstanding legs of the angles 10 and 11 to provide recesses for the shoulders 23 of the prongs 18 and 19 whereby to avoid loss in capacity of the 50 binder due to the thickness of the said shoulders 23 of the prongs 18 and 19. The upstanding legs of the angles 10 and 11 are each provided with a suitable aperture 25 therethrough disposed opposite the end of each round prong 18 for receiving 55 the end of the round prongs 18 as best indicated in Fig. 4 to prevent filler sheets 21 from becoming disimpaled when the binder is closed.

The novel loose leaf binder disclosed herein may be provided with any suitable locking device 60 to lock the angles 10 and 11 of the angle back thereof in a closed or partially opened position. The applicant prefers to use a locking device similar to the locking mechanism disclosed and claimed in the application for patent of Stanley 65 G. Johnson, Serial No. 62,885, filed February 8, 1936, which issued into Patent No. 2,110,366 entitled Loose leaf binder on March 8, 1938.

70 Referring now particularly to Figs. 2, 3, 4 and 5, the said locking device comprises a locking lever 75 26 having a locking finger 27, an operating key

28 and an inverted U-shaped central portion 29 through which a rivet 30 is positioned for securing the said locking lever 26 in pivotal relationship to the end piece 16 of the angle 11. The said U-shaped central portion 29 of the said locking lever 26 bridges over or straddles the end piece 16 in such a manner that a spring 31 coiled around the rivet 30 maintains the locking finger 27 of the said locking lever 26 in sufficient spaced relationship to the end piece 16 as to permit the end 10 piece 14 of the angle to rotate between the said locking finger 27 and the end piece 16 when the binder is being opened and closed. The said spring 31 coiled around the rivet 30 has one end thereof retained in a fixed position against the 15 hinge leg of the angle 11 between an inwardly disposed tab 32 struck up from the said hinge leg of the angle 11 and the end piece 16 thereof, while the other end of the said spring 31 constantly urges the locking lever 26 to rotate toward its 20 locked position by means of constant pressure exerted by the said spring 31 against the bottom of the horizontally disposed operating key 28 of the said locking lever 26. A suitably disposed ratchet type detent 33 secured to the angle 10 or 25 end piece 14 thereof is engaged by the locking finger 27 as the binder is closed from the position shown in Fig. 7 to the positions shown in Figs. 6 and 4. When closing the binder the locking finger 27 of the locking lever 26 acts as a 30 pawl or click riding over the ratchet type detent 33. Obviously, any number of ratchet teeth may be used in the detent 33 in order to provide a like number of partially opened positions of the binder.

The cover assembly comprises front and back covers 34 and 35 respectively and the U-shaped back 17 which are secured in the proper relationship to the metal angle back of the loose leaf binder disclosed herein by means of rivets 36 extending through the upstanding legs of the angles 10 and 11 of the said angle back. The top and bottom sides of the U-shaped back 17 are each provided with a binder board filler strip 37 and a securing strip 38 preferably of pressed fiber 45 board. The said filler strip 37 has suitably spaced apertures 39 therethrough for receiving the protuberances on the outside of the upstanding legs of angles 10 and 11 and the head 24 formed on the butt end of the prongs 18 and 19, thereby permitting the said filler strip 37 and securing strip 38 to be secured to the said metal angle back in parallel relationship thereto.

The center of the said U-shaped back 17 is preferably notched on the inside thereof as indicated by the numeral 40 in Figs. 1 and 4 to permit sharp central concave flexing of the said U-shaped back 17 when the binder is partially or fully opened as indicated in Figs. 6 and 7. Each upstanding leg of the angles 10 and 11 of the 60 hinged metal angle back is bent outwardly at its upper edge to form a longitudinally disposed outwardly disposed strip 41 which provides means for accomplishing a neat abutment between the metal angle back and the flexible joint securing 65 the front and back covers 34 and 35 respectively to the U-shaped back 17.

Referring now particularly to Figs. 6 and 7 it is obvious that the three hole filler sheets 21 are held accurately in place in the novel loose leaf binder disclosed by means of one round prong 18 and the round side of one of the half round prongs 19 when the binder is partially or fully opened. The sharp edge of the half round prong 19 cannot possibly cut the filler sheets because in 75

no case does the sharp edge of the half round prongs 19 serve as a retainer or guide for the said filler sheets 21.

It is obvious that the three hole filler sheets 5 may be quickly impaled on one round prong and one half round prong and that the said filler sheets, once impaled, may be readily turned from one side of the binder to the other as in a ring binder because the said filler sheets are accurately guided at all times. The binder may be used in a partially opened position as shown in Fig. 6 and the filler sheets may be turned without disimpaling and reimpaling them which is not possible in ring binders. Obviously, when in a 15 partially opened and open position, the novel binder disclosed herein has all of the beneficial attributes of both ring and prong binders without the inherent disadvantages of them. It is very easy to impale sheets in the novel binder 20 closed inasmuch as only two holes of the three hole filler sheets need be slipped over impaling prongs.

Although the novel loose leaf binder has been shown and described as one which is specially desirable for us in binding three hole filler sheets, 25 any number of prongs may be used in connection with a single pair of cooperating opposed half prongs for obtaining like advantageous results.

Although but one embodiment of the invention has been disclosed and described in detail, it will be understood that various changes including the size, shape, arrangement and detail of the parts thereof may be made without departing from the spirit of the invention, and it is not intended to limit the scope of the invention other than by the terms of the appended claim. 5

I claim:

In a hinged angle back loose leaf binder having 10 a plurality of leaf impaling prongs projecting from the upstanding legs of the angles of the angle back thereof adapted for use with filler sheets having three impaling apertures there-through, the combination of a pair of centrally 15 disposed opposed arcuate half round leaf impaling prongs adapted to register with each other and with the central sheet aperture when the binder is partially or fully closed and one arcuate round leaf impaling prong projecting from each 20 angle of the said angle back spaced laterally from the flat face of each of the said half round prongs to engage the corresponding end sheet aperture. 25

EDWARD H. ZERBE. 25
